(57) **CLAIM**

I claim the ornamental design for a mouthpiece, as shown and described.

DESCRIPTION

FIG. 1 is a perspective view of a mouthpiece;
FIG. 2 is a front view of the mouthpiece from FIG. 1;
FIG. 3 is a back view of the mouthpiece from FIG. 1;
FIG. 4 is a right side view of the mouthpiece from FIG. 1;
FIG. 5 is a left side view of the mouthpiece from FIG. 1;
FIG. 6 is a top view of the mouthpiece from FIG. 1; and,
FIG. 7 is a bottom view of the mouthpiece from FIG. 1.
The features shown in broken lines in the drawings depict
portions of the mouthpiece that form no part of the claimed
design.

1 Claim, 7 Drawing Sheets
